(57) **CLAIM**

The ornamental design for a hexagonal carton, as shown and described.

DESCRIPTION

FIG. 1 is a perspective view of a hexagonal carton showing the first embodiment of my new design;

FIG. 2 is a front elevational view of the hexagonal carton of FIG. 1, the opposite side being a mirror image thereof;

FIG. 3 is a top plan view of the hexagonal carton of FIG. 1;

FIG. 4 is a right side elevational view of the hexagonal carton of FIG. 1;

FIG. 5 is a left side elevational view of the hexagonal carton of FIG. 1;

FIG. 6 is a bottom plan view of the hexagonal carton of FIG. 1;

FIG. 7 is a perspective view of a hexagonal carton showing the second embodiment of my new design;

FIG. 8 is a front elevational view of the hexagonal carton of FIG. 7, the opposite side being a mirror image thereof;

FIG. 9 is a top plan view of the hexagonal carton of FIG. 7;

FIG. 10 is a right side elevational view of the hexagonal carton of FIG. 7;

FIG. 11 is a left side elevational view of the hexagonal carton of FIG. 7; and,

FIG. 12 is a bottom plan view of the hexagonal carton of FIG. 7.
